UNITED STATES PATENT OFFICE.

RICHARD HENRY ADAMS, OF COBALT, ONTARIO, CANADA.

PERCUSSIVE ROCK-DRILLING APPARATUS.

1,269,147.

Specification of Letters Patent. Patented June 11, 1918.

Application filed May 10, 1917. Serial No. 167,650.

To all whom it may concern:

Be it known that I, RICHARD HENRY ADAMS, a subject of the King of Great Britain, residing at the town of Cobalt, in the county of Nipissing and Province of Ontario, Dominion of Canada, have invented certain new and useful Improvements in Percussive Rock-Drilling Apparatus; and I hereby declare that the following is a full, clear, and exact description of the same.

This invention relates to a percussive rock drilling apparatus containing certain novel features of construction which permit of greatly-increased efficiency with corresponding advantageous operation, and it relates more particularly:

(a) To a sensitive control of the compressed air admitted into the cylinder, the object of this feature of the invention being to economize the use of the air, which, in all mining and drilling operations, is a factor of considerable expense, this object being attained by providing the cylinder in the vicinity of the front and back heads with relatively short inlet ports leading direct from the air chest transversely through the cylinder and its surrounding jacket, and by providing the air chest with a tubular air container having ports which, during the reciprocation of the container, register alternately with said air inlet ports and feed the compressed air therethrough, the cylinder being provided with reversing ports by which the air container is actuated to feed the air alternately to said inlet ports;

(b) To certain details in the construction of the cylinder and the means provided for scavenging the air when the piston reverses its movement;

(c) To the rotating device by which the piston can be caused to either revolve or gyrate during the operation of the drill;

(d) To providing the front end of the cylinder with a countersunk seat for the front cylinder head and thus eliminate any structural feature from the interior of the cylinder tending to either interfere with the operation of the piston or to result in the injury or destruction of the apparatus;

(e) To the means by which the drill is secured to the drill stock, such means consisting of a movable key compressed against the drill shank by means of a chuck having a tapering chamber so disposed with relation to the drill stock that the percussive action of the drill tends to tighten the pressure

of the chuck against the key and the corresponding pressure of the key against the drill shank;

(f) To preventing the leakage of air past the piston heads by constructing the piston rings of two semi-circular sections, so that they can be easily fitted into the piston grooves, and providing each section with projecting tongues, which, when the piston rings are assembled, will overlap the corresponding tongues of the other section; and,

(g) To providing the shell with laterally-adjustable slideways, by which the wear, either of the slides or the slideways, may be taken up to prevent the lateral movement of the cylinder, while permitting of its free axial movement.

In the drawings:—

Figure 1, is a sectional elevation of the cylinder and its related parts;

Fig. 2, is an end elevation of the slide;

Fig. 3, is a side elevation of the slide;

Fig. 4, is a plan view of the slide; Figs. 5 and 6, are detail views of the piston ring; and,

Fig. 7, is a sectional elevation of the cylinder with the piston removed.

Like characters of reference refer to like parts throughout the specification and drawings.

a represents the cylinder, which is of the usual shape and dimensions; *b* represents a jacket surrounding the cylinder *a*, and forming with it an exhaust chamber *c*; and *d* represents an air chest, integral with, or attached to the jacket *b*, provided with an air intake *e*.

Within the air chest *d* is a tubular air container *f* having a port *g* through which the air flows, continuing from the air intake *e* into the container, this port being elliptical or elongated, so that a part of it will always be in line with the air intake *e*, regardless of the position of the tubular air container during its stroke. The ends of the air container *f* are closed by heads *h*, *h'*, and formed through the wall of the air container adjacent to the heads *h*, *h'*, are ports *i*, *i'* which register during the stroke of the valve with corresponding ports *j*, *j'*, respectively, leading directly from the air chest into the cylinder in the vicinity of the front and back heads *k*, *k'*, respectively. The length of the ports *k*, *k'* is relatively short, so that there will be no storage therein of any considerable quantity of compressed air

during the operation of the apparatus, to be wasted during the exhaust.

In a full-sized apparatus, these ports *k*, *k'* are from three-quarter inch to an inch in length, one-quarter inch in depth, and about one and one-quarter inches in width, which will entail a loss at each stroke of the piston of approximately five-sixteenths of a cubic inch of air; whereas, in the present 10 type of rock drilling apparatus, where the air is taken from the center of the air chest and carried by an air duct axially of the cylinder to the vicinity of the cylinder heads, there is a loss of approximately seven and 15 one-half cubic inches at each stroke, or a loss of about twenty-four times that of the present construction.

The outer surface of the wall of the air container *f* is apertured, as shown at *l*, to 20 reduce the weight of the container, the air being unable to find an outlet through the apertures *l*, owing to the contact of the air chest with the structural parts of the container.

25 The wall of the container *f*, adjacent to the ports *i*, *i'*, is recessed as shown at *m*, *m'*, and leading through the jacket *b* to the exhaust chamber *c*, are ports *o*, *o'* with which these recesses *m*, *m'* register during the 30 movement of the air container, the ports *o*, *o'* being contiguous to the ports *j*, *j'*, so that the recesses *m*, *m'* may, during the stroke of the container, couple the ports *j* and *o*, and the ports *j'* and *o'*, respectively, 35 to enable the air within the cylinder being forced out through the ports *j*, *j'* to the recesses *m*, *m'* and through the ports *o*, *o'* to the exhaust chamber *c*, from which it escapes by means of the exhaust ports *p*, *p'*.

40 As the ports *j*, *j'*, *o*, *o'* and *p*, *p'* are relatively small in proportion to the cross-sectional area of the cylinder, there can be no sudden expansion during the return movement of the piston, resulting from the 45 exhaust of the compressed air through the ports *j*, *j'* and *o*, *o'* into the exhaust chamber *c*, nor any sudden expansion of the air as it passes from the exhaust chamber *c* through the exhaust ports *p*, *p'* to the atmosphere. 50 In this way, a substantially uniform temperature is maintained in the cylinder, the maintenance of which prevents the piston and cylinder freezing together, and enables the apparatus to continuously operate under 55 normal conditions.

In the back cylinder head *k'* and in line with the inlet port *j'*, is an air chamber *q*, having a set of diagonally-arranged ports *q'* to deliver the air on the back piston head *r*, 60 which is provided with a turbine or rotating device *r'*. Between the piston heads *r* and *s*, is the gyrator *t*, which consists of a set of spiral grooves *t'* and a nut *t''*. The inner face of the nut *t''* is provided with 65 teeth *t''*, which enter the spiral grooves *t'*

to cause the gyration of the piston, and its outer surface is provided with ratchet teeth *v* engaged by pawls *v'* which permit of the forward gyration of the piston and prevent its reverse gyration. The pawls *v'* are carried by forks *v''* extended into the cylinder from the exterior of the apparatus, the forks engaging the nut *t''* to prevent its axial movement during the reciprocation of the piston, and to permit of its forward, and 75 prevent the reverse, rotation during the gyration of the piston. By this means, a partial rotation of the piston may be effected at each stroke of the piston.

If the drill should be required to continuously rotate during the reciprocation of the piston, the forks *v''* and pawls *v'* may be withdrawn, and in that case, the nut *t''* can reciprocate and rotate with the piston without imparting a gyrating movement 85 to it.

To reverse the movement of the air container, the cylinder is provided with two air ducts *w*, *w'*, the air duct *w* leading from the front part of the cylinder into the air 90 chest near its back head, and the air duct *w'* leading from the back part of the cylinder into the air chest near its front head.

The air entering the air chest *d* through the air intake *e*, passes through the port *g* 95 into the tubular air container *f*, and when the port *i* is in line with the port *j*, passes into the cylinder *a* in the vicinity of the front cylinder head *k*, against which it operates to force the piston in the direction 100 of the back cylinder head *k'*.

When the front piston head *s* clears the port of the air duct *w*, some of the air within the front part of the cylinder passes through the duct *w* into the air chest *d* at 105 the back of the container head *k'* and forces the container in a forward direction, as indicated by arrow in Fig. 1.

This movement of the container brings the port *i* out of line with the port *j* and 110 brings the port *i'* into line with the port *j'*, and the recess *m* into position to couple the port *j* with the port *o*. The compressed air then flows through the ports *i'* and *j'* into the air chamber *q*, from which it is directed 115 by the ports *q'* against the back piston head *r*, to cause the rotation of the piston and drive it in the direction of the front cylinder head. While the piston is moving in the direction of the front cylinder head, the front 120 piston head *s* forces the air in the front part of the cylinder through the port *i*, recess *m*, port *j*, to the exhaust chamber, out of which it passes through the exhaust ports *p*, *p'*.

When the front piston head passes the 125 port for the air duct *w*, the air in that duct can find a passage around the gyrator *t* to the exhaust port *x* for the cylinder *a*, through which it escapes to the atmosphere, there being a space between the gyrator and 130

the cylinder wall of sufficient dimensions to admit of the air in the ducts w , w' and in the air chest between the container and the chest heads, being immediately exhausted 5 during the cycle of action.

When the back piston head r passes the port for the air duct w' , the air passes from the back part of the cylinder through the duct w' into the air chest in front of the container head h , and moves the container in the opposite direction to that indicated by arrow in Fig. 1.

This has the effect of moving the port i' out of line with the port j' and bringing the 15 port i again into line with the port j and the recess m' into position to couple the ports j' and o' , so that when the piston is reversing its movement, *i. e.*, moving in the direction of the back cylinder head, the air 20 will be scavenged through the ports j' and o' to the chamber c and escape through the exhaust ports p , p' .

This action of the air container has the effect of supplying only sufficient air to the 25 cylinder to move the piston to the limit of its stroke in either direction, and avoids the accumulation in the passages or ports leading from the air chest to the cylinder, of a quantity of compressed air which is not 30 used for driving purposes. The economy in this respect, although relatively insignificant at a single stroke of the piston, amounts to a large volume in the course of a day's operation, and saves about fifty per cent.

85 of the operating charges.

To prevent a leakage past the piston heads, these heads are grooved, as shown at a' , and contained in the grooves are piston rings b' , similar to those shown in Figs. 5 40 and 6, each of these piston rings consisting of two semi-circular sections, each semi-circular section having a lap-joint b'' corresponding with the lap-joints of the other section, so that no channel will be formed, 45 even as a result of the wear on these parts, through which the air can escape past the piston heads; it being necessary to make them in two sections, each of which can be independently fitted in its groove, as the 50 weight and inelasticity of the ring prevents it being sprung into position, as in the case of ordinary piston rings.

All of the foregoing features contribute to the economy of operation, and it has been 55 estimated that the saving in compressed air alone averages one hundred and fifty dollars per month per drill.

The piston rod c' extends beyond the front 60 piston head s , and is formed with a fillet c'' in front of the piston head to strengthen it. The front cylinder head h is formed with a correspondingly-shaped bevel e'' , so that when the piston reaches the limit of its stroke in a downward direction, the fillet will enter 65 the bevel e'' , but without coming in contact

with the front cylinder head, but if it should drive past the limit of its stroke, the feature of the fillet and the bevel will prevent any serious damage being done to the front cylinder head, as no projecting part 70 of the cylinder head, such as a boss, is presented to the piston head to be riveted or hammered during the cycle of action.

To maintain the correct alignment of the front cylinder head, the cylinder is formed 75 with a countersunk seat f' at its front end, into which the front cylinder head enters, this countersunk seat holding the front cylinder head in its set position without presenting any interior parts to the front piston head, thus obviating the trouble which has heretofore arisen through the presence of an interior boss on the front cylinder head within the cylinder, such boss usually being hammered by the front piston head during 80 the movement of the piston until a breakage occurs, and the drill is put out of action.

The drill stock g' is circumferentially apertured at g'' for the wedge l' , which engages the drill shank when inserted in the 90 drill stock, the wedge l' having a head l'' and being engaged by a cylindrical chuck s' . This chuck s' consists of a cylindrical wall s'' , and end flanges y having a central bore x' of corresponding diameter to the 95 drill stock, so that the chuck will snugly fit thereon.

The interior surface of the wall s'' is tapered with its contracted end toward the back of the drill stock, to engage and compress the wedge adjacent the drill shank as it is moved forward, the flanges y engaging the wedge and limiting the movement of the chuck in either direction on the drill stock. To insert the drill shank into the drill stock, 100 the chuck is moved toward the front cylinder head, which movement continually increases the diameter of the interior surface of the wall s'' until the chuck has reached its limit of movement in that direction, the 105 maximum internal diameter of the chuck then being sufficient to release the pressure of the wedge from the drill shank.

When the chuck is in this position, the 110 drill shank can either be inserted in or withdrawn from the drill stock. When the drill shank is inserted in the drill stock, the movement of the chuck is reversed, and the wall of the chuck continually contracts upon the wedge until no further movement is possible, and securely clamps the drill shank in the drill stock.

During the operation of the apparatus, the striking of the drill on the rock has the 115 tendency to increase the pressure of the chuck against the wedge, and the wedge against the drill shank, until no further pressure is possible, it being necessary to release the chuck by pounding it with a soft-metal hammer.

One of the sources of most frequent trouble is the wear on the fixed slides of the cylinder and slideways of the shell, this wear permitting of the lateral movement of the cylinder. To overcome this, I have provided the shell r' with adjustable slideways r'' , and to accomplish the adjustment, I have formed the body of the shell with elongated slots z , disposed transversely to the length 10 of the shell, and have provided the slideways with adjusting bolts z'' which are inserted through these slots to permit of the lateral adjustment of the slideways to each other and to the slides z' of the cylinder. 15 This lateral adjustment keeps the slides and slideways constantly in contact with each other, and in this way, prevents any side movement during either the adjustment of the cylinder or the operation of the apparatus. 20

While this may appear, in itself, a trivial alteration, still, it is of the utmost importance, in view of the fact that it is necessary for the drill to strike the same spot at each 25 operation of the piston.

Having thus fully described the nature of my invention, what I claim as new and desire to secure by Letters Patent, is:

1. A percussive rock-drilling apparatus 30 comprising a cylinder having a piston therein and a central exhaust port within the boundaries of the stroke of the piston heads, a jacket surrounding the cylinder, and forming with it an exhaust chamber having outlet ports, an air chest having inlet ports into 35 the cylinder adjacent to the cylinder head and exhaust ports into the exhaust chamber in the vicinity of the inlet ports, and valve-reversing ports in the vicinity of the 40 air-chest heads leading to opposite sides of the center of the piston stroke, and a reciprocating tubular air-valve in the air-chest having ports registering with the inlet ports of the cylinder and recesses in its cylindrical 45 wall coupling the inlet and exhaust ports during the reciprocation of the valve.

2. A percussive rock drilling apparatus

comprising a cylinder having an inlet port adjacent to each cylinder head, an air chest for the cylinder having an air intake, a tubular air container within the air chest having a port through which the air flows into it continuously from the air intake, the ends of the container being closed and the wall of the container being provided with ports to 55 register during the cycle of action with the ports leading into the cylinder, the wall of said container being recessed in the vicinity of said ports, and an exhaust chamber surrounding the cylinder having exhaust ports 60 leading to the atmosphere and ports communicating with the air chest in the vicinity of the inlet ports for the cylinder and coupled therewith by the recesses in the wall of the container during the cycle of action. 65

3. A percussive rock drilling apparatus comprising a cylinder, a piston therein, an air chest connected with the cylinder by relatively short inlet ports leading direct into the cylinder in the vicinity of the cylinder heads, a reciprocating tubular air container within the air chest having ports registering during its reciprocation alternately with said air inlet ports, and reversing ports leading from the cylinder to the air chest, 70 controlled during the cycle of action by the piston, to cause the tubular air container to reciprocate alternately in opposite directions, an exhaust for the reversing ports, an exhaust chamber surrounding the cylinder, 75 having exhaust ports leading to the atmosphere and ports communicating with the air chest in the vicinity of the inlet ports for the cylinder, and coupled therewith by recesses in the wall of said container, during 80 the cycle of action, to provide for the scavenging of the cylinder during the reversal of the piston.
